UNITED STATES PATENT OFFICE

135,464

DESIGN FOR A NURSE'S CAP

Sylvia Seigenfeld, New York, N. Y., and Emily Alexander, Stamford, Conn.

Application February 3, 1943, Serial No. 109,444

Term of patent 3½ years

To all whom it may concern:

Be it known that we, Sylvia Seigenfeld and Emily Alexander, citizens of the United States, residing at New York city, New York, and Stamford, Connecticut, respectively, have invented a new, original, and ornamental Design for a Nurse's Cap, of which the following is a specification, reference being had to the accompanying drawings, forming part thereof.

Fig. 1 is a plan view of a nurse's cap, showing our new design,

Fig. 2 is a side elevational view thereof in the position it will assume when being worn,

Fig. 3 is a rear elevational view, and

Fig. 4 is a front elevational view thereof.

We claim:

The ornamental design for a nurse's cap, as shown.

SYLVIA SEIGENFELD.
EMILY ALEXANDER.
